UNITED STATES PATENT OFFICE.

NAPOLEON DUSSAULT, OF MONTREAL, CANADA, ASSIGNOR TO JOSEPH ADAM, OF SAME PLACE.

HAND LASTING-TOOL.

SPECIFICATION forming part of Letters Patent No. 658,765, dated October 2, 1900.

Application filed December 11, 1899. Serial No. 739,881. (No model.)

To all whom it may concern:

Be it known that I, NAPOLEON DUSSAULT, a subject of Her Majesty the Queen of Great Britain, residing in the city and district of 5 Montreal, Province of Quebec, Canada, have invented certain new and useful Improvements in Hand Lasting-Tools; and I do hereby declare that the following is a full, clear, and exact description of the invention, such as 10 will enable others skilled in the art to which it appertains to make and use the same.

This invention relates to hand lasting-tools; and its object is to provide a tool of this character which is simple in construction, of few 15 parts, effective in operation, and which may be manufactured at a modern cost.

To these ends the invention consists in a hand lasting-tool constructed substantially as hereinafter illustrated and described, and 20 defined in the appended claims.

Referring to the drawings, in which similar letters of reference indicate similar parts, Figure 1 is a view in perspective of a hand lasting-tool constructed in accordance with 25 this invention. Fig. 2 is an elevation thereof, the parts being in the position assumed prior to driving the nail. Fig. 3 is a view similar to Fig. 2, showing the opposite side of the tool. Fig. 4 is a view similar to Fig. 30 2, parts being shown in section to show the construction. Fig. 5 is a view, partially in section, showing the position assumed by the parts when the nail is driven and cut. Figs. 35 6 and 7 are views in perspective of the operating lever-handles. Figs. 8, 9, 10, and 11 are views in perspective of details of construction.

Hand lasting-tools as heretofore constructed have generally been very complicated, comprising 40 many parts and entailing great expense in their manufacture. In the type shown in the patent to Fréchette, No. 594,241, on which this invention is an improvement, not only are the objections above noted apparent, but there exists the further objection that in the event of the nail being broken or of failure to be properly fed to the plunger it is necessary to take the tool apart in order 45 to bring the nails down into their operative position, thus necessitating a serious loss of time and involving considerable trouble and

inconvenience. In the tool about to be described all of these defects and objections are obviated and a hand lasting-tool provided which, in the event of the failure of the nails 55 to be properly fed to the plunger or of breakage of the same, does not need to be taken apart or otherwise manipulated, thus saving time and trouble, in addition to the advantages of simplicity of construction and operation and reduced cost of manufacture. 60

In the drawings, A and B represent two levers suitably pivoted together and provided with handles A' and B' and jaws A² and B². The lever B has a lug b on its under side, having 65 a roughened face. The lever A is provided at the outer end with a frame A³, in which is formed an opening a, extending therethrough from top to bottom. In the upper portion of the frame A³ is fixed a plug a', 70 which has its sides inclined from top to bottom and is provided in its upper portion with a passage-way a² for the nails, as clearly shown in Figs. 4 and 5, said passage-way being exposed on one side for substantially its 75 entire length. The passage-way a² communicates with the opening a, and a suitable leaf-spring a³ is secured to the upper portion of the plug a' and bears at its lower portion against the inclined side of said plug. 80

The outer portion of the frame A³ is provided with an upwardly-extending lug a⁴, to the upper portion of which are pivoted the bifurcated arms d of a hand-lever D. To the arms d of the lever D is pivoted the plunger 85 D', the lower end of which is split, forming the spring-clamp d', which is provided with a suitable binding-screw. A threaded perforation d² is formed in the lower portion of the plunger D' and communicates with open-sided 90 channels d³, formed upon the adjacent faces of the clamp d'. A feed-rod or nail-driver D² is threaded in the perforation d² and is seated in the grooves d³, the lower end of said feed-rod projecting beyond the edge of the plunger 95 D' and extending into the opening a of the frame A³. The extremity of the feed-rod D² is suitably sharpened for cutting off the nails.

In the body portion of the plunger D' is formed an opening d⁴, which is enlarged at 100 its lower portion, forming the inclined side or cam-surface d⁵, which serves as a bearing-

surface against which the friction-roller e of the guiding-bracket E engages. The bracket E is constructed with the spaced sides e' , between which the roller e is journaled. The 5 sides e' of the bracket E embrace the sides of the frame A^3 and are rigidly secured thereto by suitable screws threaded into the sides of the frame and the upper portion of the jaw A^2 .

A suitable spring D^3 is secured at its lower 10 end to the plunger D' and at its upper end to the lug a^4 , which tends to retract the plunger when it is released from pressure and also holds the feed-rod in proper position relative to the opening a of the frame A^3 . If desired, 15 a spring D^3 may be provided upon each side of the frame. A suitable spring D^4 may be employed to open the jaws A^2 B^2 .

The lever A is provided at a suitable point 20 on its upper side with a lug f , to which is rotatably secured a reel F . The lasting-nails f' are formed continuous with each other and are wound upon the reel F .

In operating the improved lasting device 25 above described the lasting-nails are passed through the perforation in the plug a' and down between the inclined sides thereof and the leaf-spring a^3 , whereby the nails are held in their operative position ready to be fed to the work. The nails are then passed down 30 through the opening a of the frame A^3 between the point of the feed-rod D^2 and the inner face of the jaw A^2 , as clearly shown in Figs. 4 and 5. The parts are now in the position shown in Fig. 4, and the tool is ready for 35 operation. The lever-handles A' and B' are grasped with one hand and the jaws A^2 and B^2 closed upon the work. The hand-lever D is then forced downwardly, and the sharp point of the feed-rod engages the nail just 40 back of the head and forces the same into the work. As the plunger descends the friction-roller e of the bracket E rides against the cam-surface d^5 of the opening d^4 and draws the plunger D' , and with it the feed-rod D^2 , 45 with increasing force toward the frame A^3 , until at the end of the stroke the cutting-point of the feed-rod severs the lasting-nail, which has been driven up to its head in the work, the parts assuming the position shown 50 in Fig. 5. Upon releasing the hand-lever D the plunger is returned to the position shown in Fig. 4 by means of the spring D^3 , the point of the feed-rod sliding back above the head of the next nail to be driven. A suitable stop- 55 plate A^4 is pivoted to the frame A^3 and adapted to engage a lug on the hand-lever D to lock the parts in their raised position when desired.

By providing the stop-plate A^4 the feeding 60 mechanism may be positively held from movement, enabling the levers A and B , with their gripping-jaws, to perform the function of the ordinary lasting-pincers, in addition to which the tendency of injuring the mechanism, if it is desired to use the head b as a hammer, is 65 eliminated.

As shown, the plunger D' is mounted at a point to one side of the frame A^3 , and the

relative movement of the cam-surface and the guide serve to impart a movement to said plunger at the time when the severing takes place, which carries the feed-rod or nail-driver across the path of movement of the nail-strip in a diagonal or oblique direction and with increasing force, which not only severs the nail, but has a tendency to form a 75 somewhat sharpened edge on the succeeding nail. Having this movement and obtaining a double result thereby, I provide the feed-bar, which is removable and adjustable, and secure it in such a manner that the pressure 80 applied by the hand-lever D is exerted in the direction of its longitudinal center, in a manner similar to a chisel, in contradistinction to a cutting feed-bar, in which the cutting-point moves in a direction substantially at 85 right angles to its longitudinal center, the pressure in the latter case being borne by one end of the feed-bar. In other words, I secure the feed-bar in the plunger at an angle which is substantially the same as the 90 angle through which the feed-bar travels during the severing operation.

By the use of the removable and adjustable feed-bar arranged in the manner described I am able to construct it of light weight, as 95 well as small, without loss of strength, in addition to which the cutting-point can be readily sharpened.

By forming the passage-way for the nail-strip substantially open sided there is no 100 necessity of taking the device apart in case trouble should arise during the passage of the nail-strip therethrough.

It will be seen from the construction above described that if a nail breaks off above the 105 feed-rod it is only necessary to again raise the plunger to its full height, whereupon the feed-rod will engage and drive down the next nail, or if a defective nail is engaged it is only necessary to operate the hand-lever and cut it off until a perfect nail is reached. Hence it will be seen it is never necessary to remove the parts of the tool to insure the proper feeding of the nails or remove broken or bent nails.

While I have herein shown a preferred 115 form of carrying my invention into effect, yet I do not desire to limit myself to such preferred details of construction, but claim the right to use any and all modifications 120 thereof which will serve to carry into effect the objects to be attained by this invention in so far as such modifications and changes may fall within the spirit and scope of my 125 said invention.

I claim—

1. A hand lasting-tool comprising two pivotally-connected levers having gripping-jaws; a frame carried by one of said levers; a hand-lever pivotally connected thereto; a nail driving and severing plunger pivotally connected to said hand-lever, said plunger having a cam-surface; and a stationary guide carried by said frame against which said sur-

face is adapted to ride during the movement of said hand-lever, whereby said plunger will be caused to be positively forced toward said frame.

5. 2. A hand lasting-tool comprising two pivotally-connected levers having gripping jaws; a frame carried by one of said levers, said frame having a passage-way for the nail-strip, said passage-way being exposed for substantially its entire length; a hand-lever pivoted to said frame; a nail driving and severing plunger pivotally connected to said hand-lever; and means for positively forcing said plunger toward said frame, substantially as described.

3. In a lasting-tool, the combination with two pivoted levers provided with jaws; of a hand-lever pivoted to one of said levers, a nail-driving plunger pivoted to said hand-lever and provided with an opening having an inclined side; a feeding and cutting rod mounted in said plunger; a bracket fixed upon one of said pivoted levers and having a friction-roller adapted to engage said opening and bear against said inclined side, whereby the said plunger is forced toward and into the path of movement of the nail-strip during its downward movement, whereby the nail is driven to its seat and severed, substantially as described.

4. In a lasting-tool, the combination with two levers provided with jaws; of a frame

fixed on the end of one of said levers, having an opening therethrough; a plug secured in said opening, having an orifice communicating with said opening for the passage of the nails; a lug mounted on said frame; a hand-lever pivoted upon said lug; a plunger pivoted to said hand-lever; a feeding and cutting rod mounted in said plunger; and means for forcing the said plunger toward the said frame during its downward movement, whereby the nail is driven to its seat and severed, substantially as described.

5. The combination with a hand lasting-tool having a reciprocating nail-driver; and a hand-lever for imparting movement thereto; of a pivotally-mounted stop-plate adapted to lock said lever in an inoperative position.

6. In a hand lasting-tool, a plunger, having its lower end arranged at an angle to its longitudinal center, said end having a screw-threaded opening and also having a spring-clamp; and a cutting nail-driver having a portion of its length screw-threaded, removably and adjustably secured in said opening and clamp, substantially as described.

In witness whereof I have hereunto set my hand in the presence of two witnesses.

NAPOLEON DUSSAULT.
